UNITED STATES PATENT OFFICE.

HENRY BERNARD MEES, OF NADEAU, KANSAS.

BEAD-LOOM.

SPECIFICATION forming part of Letters Patent No. 758,376, dated April 26, 1904.

Application filed November 25, 1903. Serial No. 182,615. (No model.)

To all whom it may concern:

Be it known that I, HENRY BERNARD MEES, a citizen of the United States, and a resident of Nadeau, in the county of Jackson and State 5 of Kansas, have invented a new and Improved Bead-Loom, of which the following is a full, clear, and exact description.

This invention relates to certain novel and useful improvements in bead-looms, and is particularly adapted for holding the threads upon 10 which the beads are to be strung.

In carrying out my invention I have particularly in view the provision of a small loom which will hold the warp-threads apart in such 15 manner that they may be stretched taut and equal distances apart, thereby obviating the possibility of the threads loosening and spoiling the work.

Another object of my invention is to provide 20 a clamping device for holding a portion of the beadwork that has been completed, so that the warp-threads upon which the beads are to be strung may be held in a convenient position for the operator.

A further object of my invention is to provide 25 a loom of the character described which will embody the essential and desired features of simplicity, durability, convenience, and inexpensiveness.

With the above objects and others of a like 30 nature in view my invention consists in the construction, combination, and arrangement of parts, as is described in this specification, delineated in the accompanying drawings, and 35 set forth in the appended claims.

Reference is to be had to the accompanying 40 drawings, forming a part of this specification, in which similar characters of reference indicate corresponding parts in both the figures.

Figure 1 is a perspective view of a loom embodying my invention, showing the manner 45 of holding the work thereon. Fig. 2 is a vertical sectional view taken through the loom on the line 2-2 of Fig. 1.

Referring now to the accompanying drawings, 50 5 designates the base portion of the machine, which may be of any suitable size and constructed of any desired material. Extending vertically from the side edges of this base,

near the end portions thereof, are standards 50 or supports 6 6 7 7, said standards in the present instance being preferably substantially triangular in form. Journaled in the upper end of each set of standards is a rod 8, having coiled about the same a spiral spring 9. These 55 springs, it will be observed, lie between the standards, and the coils of the same may be tightened—that is to say, the coils may be brought into contact or permitted to expand—through the medium of a thumb-nut 10, threaded 60 upon one end of the rod, each rod being provided with one of said thumb-nuts.

The warp-threads *a*, upon which the beads *b* are strung, are held between the coils of the springs, as is clearly seen in Fig. 1—that is 65 to say, the threads are stretched in parallelism from one spring to the other, and when the edges of the threads have been passed between the coils of the springs the latter may be tightened, as heretofore stated, by turning 70 the thumb-nuts.

In order to retain or hold the portion of the beadwork which has been finished—such, for instance, as the part *c*, (shown in Fig. 1)—I have provided a clamp in the form of a 75 crank-rod 11, journaled in the lower portion of the standards 7 7, said rod being designed to be turned through the medium of the handle portion 12, so that the beadwork may be 80 securely clamped between said rod and the base-board 5, as is clearly shown in Fig. 1.

From the above description, taken in connection with the accompanying drawings, the construction and manner of employing my improved loom will be readily apparent. 85

The threads are arranged or secured in the loom in the manner shown in Fig. 1, and the beads are threaded upon the same to form any suitable design.

With a machine of this character the warp- 90 threads need not be more than one inch longer than the beadwork, thus saving from eight inches to ten inches on each thread, an advantage over the ordinary form of bead-looms now in use, in which it is necessary for the 95 warp-threads to be on an average of twelve inches longer than the article to be made.

There are other advantages incident to my

improved loom which will be readily apparent to those familiar with a device of this character, so it is unnecessary to dwell upon the same in detail.

5 Having thus described my invention, I claim as new and desire to secure by Letters Patent—

1. A loom comprising a base portion, standards secured thereto, means carried by said standards for retaining threads upon which 10 the beads are to be strung, and a clamping-rod journaled in certain of said standards and designed to clamp the finished beadwork to the base, substantially as set forth.

2. The loom herein described, comprising 15 a base portion, standards extending upward from said base portion, rods carried by and extending between the said standards, one end of each rod extending beyond one of the standards, and being threaded to receive a 20 nut, nuts turning on the extended ends of the rods and by which the standards may be adjusted toward each other, coil-springs wound on the rods between the standards and adapted to be compressed by means of the said nuts, 25 and a clamp below one of the said rods and consisting of a crank-rod having its arms journaled in the standards and its wrist portion

arranged to clamp the finished work against the base, substantially as set forth.

3. A loom comprising a base or support, 30 standards projecting therefrom and adapted at their free ends to be drawn together by a tightening means, a rod extending between the free ends of the standards and projecting through and beyond one of the standards and 35 having such projection or extension threaded, a nut on the threaded extension and a coil-spring on the rod between the standards, substantially as set forth.

4. The combination in a loom with a base 40 portion or support, and means above the same for retaining threads upon which to string beads, of a clamp below the thread-retaining means and consisting of a crank-rod having its arms journaled, and its connecting or wrist 45 portion arranged to hold the finished work, substantially as set forth.

In testimony whereof I have signed my name to this specification in the presence of two subscribing witnesses.

HENRY BERNARD MEES.
